UNITED STATES PATENT OFFICE.

JOHN W. HIPWELL, OF MAYWOOD, AND LOUIS M. HOPKINS, OF CHICAGO, ILLINOIS,
ASSIGNEES, BY MESNE ASSIGNMENTS, OF ONE-HALF TO SAID HIPWELL AND ONE-
HALF TO LOUIS A. KOHN, OF CHICAGO, ILLINOIS.

APPARATUS FOR RECEIVING BANK-DEPOSITS.

1,259,399.

Specification of Letters Patent. Patented Mar. 12, 1918.

Application filed March 10, 1913, Serial No. 753,294. Renewed April 20, 1917. Serial No. 163,538.

To all whom it may concern:

Be it known that we, JOHN W. HIPWELL, a citizen of the United States, residing at Maywood, in the county of Cook and State 5 of Illinois, and LOUIS M. HOPKINS, a citizen of the United States, residing at Chicago, Illinois, have invented certain new and useful Improvements in Apparatus for Receiving Bank-Deposits, of which the following is a specification.

The object of the present invention is to provide practical means for facilitating and making easier the depositing of money or securities in banks, or other institutions for safe keeping.

The essential elements of an apparatus used in carrying the invention into effect is a strong box or receiver, the interior of which either leads directly to the counting 20 room of a bank, or, if located at a place remote from the bank, is accessible to only an authorized representative of the bank, together with means associated with the "receiver" for automatically delivering to the 25 depositor a receipt for the package deposited, and an essential element of the present invention is means associated with the receiver for affixing to the package and to the receipt mutual identification marks, preferably 30 serial numbers, for future comparison of the envelop or other wrapper of the package and the receipt.

Another element of the invention is means for imprinting upon the package or receipt, 35 or both, a record of the day and hour (either or both) that the deposit is made.

Still another element of the invention is a lock by which the shutter of the admission slot of the receiver is kept closed, and the 40 mechanism associated with the receiver is locked to prevent its operation, until a key appropriate to the lock is properly presented to it.

Still other elements of the invention are 45 details in the construction of the apparatus and the invention consists in the features of novelty that are hereinafter described with reference to the accompanying drawings, which are made a part of this specification, 50 and in which:

Figure 1 is a sectional elevation of an apparatus embodying the invention, the strong

box or receiver and some of the other parts being shown in vertical section.

Fig. 1^a is a detail.

55

Fig. 2 is a horizontal section thereof on the line 2—2, Fig. 1, all of the parts below the cutting plane of the section being shown in plan.

Fig. 3 is an elevation of the type-form 60 face of the base section or box of the printing apparatus looking at the printing face thereof, as indicated by the arrow 3, Fig. 2.

Fig. 4 is a horizontal section thereof on the line 4—10, Fig. 3.

65

Fig. 5 is a sectional elevation thereof in different vertical planes that are perpendicular to the printing plane of the form.

Fig. 6 is an end elevation thereof, viewed in the direction of the arrow 6, Figs. 2 and 7, and showing more particularly the inking mechanism.

70

Fig. 7 is a horizontal section of a portion of the apparatus on a larger scale, on the line 7—7, Fig. 1, and showing more particularly 75 the shutter of the admission slot of the receiver and the permutation lock.

Fig. 8 is a vertical transverse section thereof on the line 8—8, Fig. 7.

Fig. 9 is a front elevation of the complete 80 apparatus.

Fig. 10 is a horizontal section, showing more particularly, the preferred form of the numbering and time indicating mechanism of the printing apparatus on the line 4—10, 85 Fig. 3.

Fig. 11 is a face view of the combined envelop or wrapper for containing the matter to be deposited, and the key for unlocking the apparatus.

90

Fig. 12 is a view of the reverse face thereof.

Fig. 13 is a face view of a coin card, which is intended to be contained in the envelop and forms a portion of the complete wrap- 95 per and key.

Fig. 14 is a perspective view thereof.

Fig. 15 is a detail view.

Fig. 16 is a horizontal section of the chute showing its two branches.

100

Fig. 17 is a perspective view of the envelop before it is closed and sealed.

The apparatus has a box or casing, 1, herein called the receiver, which is prefer-

ably made of cast metal and may be of any desired shape or capacity that will meet the requirements hereinafter described. The front wall, 2, of the receiver has through it 5 an opening, or slot, 3, for the insertion of packages adapted to contain the money or securities which it is desired to deposit in the bank, and the wrappers or inclosures of these packages must, of course, be appropriate to their purpose. For depositing checks, paper currency and coins, I prefer to use a wrapper having a pocket portion 4 and as an integrant part thereof, a check or stub, 5, the envelop being of sufficient 10 size to receive within it a coin card, 6, on one face of which a pocket for receiving paper money, checks and other securities is formed by a single piece of paper, 7, that is folded once so that one of its leaves when 15 pasted to the back of the card forms the bottom of the coin pockets, 8, while the other leaf above the fold-line is conterminous with the card, and forms the pocket. The card itself is of somewhat greater width than the 20 pocket thus formed, and that portion, 9, of it, which extends beyond the fold-line forms in effect and in fact a key, which is appropriate to the lock by which a shutter, 10, for closing the slot, 3, is held in closed position, 25 30 and other parts of the apparatus are locked so as to be incapable of operation, as hereinafter described. To this end, that portion of the card which forms the key, 9, is provided with any desired number of 35 notches, 11, 12, etc., which are adapted to register with a corresponding number of tumblers, 14, 15, etc., or portions of them which are accessible through the slot, 3. The shutter is preferably made of a com- 40 paratively thick and heavy metal plate having vertical notches, 17, 18, etc., in which the tumblers, 14, 15, etc., are located, and are free to swing about a common pivot-rod, 20, to receive which each of the tumblers is pro- 45 vided with a circular eye, or perforation, near its upper end, the pivot-rod, 20, being in turn supported by the shutter, 10, which is bored or cored to receive it. Normally, these tumblers depend by gravity from the 50 pivot-rod, 20, and each of them is provided with a finger, 21, which is radial with respect to the pivotal axis of the tumbler, but the several fingers of the several tumblers project in different radial directions from 55 the pivotal axes of the tumblers when the tumblers are pendant. These fingers occupy circumferential grooves, 22, 23, etc., formed in a shaft, 25, which is capable of both rotary and end-wise movement, so that as long 60 as the fingers are wholly between the shoulders resulting from their respective circumferential grooves, 22, 23, etc., the shaft is free to rotate relatively to the shutter, which latter has a cylindrical bore, in which 65 the shaft fits loosely. The shaft is also pro-

vided with a longitudinal groove, 26, which opens into the circumferential grooves, so that when all of the tumblers are moved about their pivotal axes until all of the fingers project in the same radial direction, the 70 shaft may be moved end-wise and the fingers will be thereby caused to enter the longitudinal groove. It is manifest that when this takes place the rotation of the shaft will carry the shutter with it, and when rotated in the proper direction the shutter will be moved away from the front wall of the receiver, and the slot, 3, thereby opened. 75

It is manifest that in order to bring all of the fingers into radial alinement, each must 80 be moved through an arc depending upon its angular position relatively to the axis of movement, and to this end the notches, 11, 12, etc., of the key are made of different depths, each appropriate to the required 85 movement of the corresponding tumbler. Hence, by giving the fingers different angular positions and making the slots of the key of correspondingly differing depths, a great number of permutations may be made. 90 The number may be still further increased by changing the distance apart of the tumblers and their corresponding notches of the key. 95

With the parts thus far described, constructed as described, the first effect of inserting the envelop or package through the slot, 3, is to unlock the shutter and permit it to be opened, but dependence is not had upon the pressure of the envelop against the 100 shutter for opening. This, however, might be done if the envelop and the contained card were made of material of sufficient strength, but in order to minimize cost it is preferable to make the envelop of stout 105 paper and the key of card-board, and where it is intended that the apparatus may receive coins, the same piece of card-board may be used for forming both the key and the coin card of known character. 110

The ends of the shaft, 25, are mounted in bearings, 27 and 28, supported by the receiver and one end of the shaft is cut away as shown at 29, leaving a non-circular projection, 30, which, as shown in the drawing, 115 is of semi-circular shape, and is adapted to be received in a corresponding socket in the bearing, 27, so that so long as the non-circular projection occupies the socket, the shaft is held against rotation, but by moving the 120 shaft end-wise to bring the non-circular projection out of its socket, the under-side of said projection will act as a journal for the shaft, and turn in the circular journal bearing, 27. Normally, the projection, 30, 125 is held in its socket by a spring 31, which surrounds the shaft and bears in one direction against it through the medium of a collar, 32, which is non-rotatively secured to the shaft, the pressure of the spring in the 130

opposite direction being transmitted to the receiver through the shutter, 10, and a washer, 33, interposed between the shutter and the end of the spring. This collar is 5 provided on one of its faces with a cam surface, which engages a complementary cam surface adjacent to the eye of a lever, 34, which eye receives the shaft loosely, so that the lever is normally free to turn thereon 10 through a limited arc, this relative movement being limited by shoulders or projections on the collar and lever, respectively, which are adapted to engage each other when the lever has been permitted to move 15 independently through the desired arc. The lower end of this lever is jointed to one end of a link, 35, the other end of which is jointed to the upper end of a lever, 36, which latter is, in turn, supported by a fulcrum 20 pin, 37, projecting from the side, 38, of the receiver. Below the fulcrum pin, 37, the lever, 36, is provided with a slotted arm, 39, and into the cam slot, 40, of this arm, projects a pin, 41, carried by a lever, 42, which 25 is non-rotatively secured to the main shaft, 43, of the apparatus. This shaft turns in suitable bearings supported by or formed with the receiver, and one of its ends projects and carries a lever, 44, having a handle, 45, by 30 which all of the parts contained within the receiver are either operated or conditioned to operate. The pin, 41, will, of course, move in an arc about the axis of the shaft, 43, and the cam slot 40, is so shaped and disposed that as the pin travels through a short portion of its permitted movement, it will bear against one side of the cam slot and rock the lever, 36, about its fulcrum, so as to move the link, 35, in the direction of the 35 arrow in Fig. 1, and thereby move the lever, 34. As before stated, the initial movement of this lever will have no effect upon the shaft, 25, but the engaging cam surfaces carried by the lever and the collar, 32, will 40 move the shaft, 25, end-wise, thereby unlocking it and permitting it to be rotated. Manifestly, this cannot take place until the key has first been presented to the accessible portions of the tumblers, 14, 15, etc., and 45 said tumblers moved to bring all of the fingers, 21, into radial alignment with the groove 26 whereby when the shaft is moved endwise said fingers will enter said groove and, thereby connect the shaft, 25, and the 50 shutter. Thus conditioned movement of the lever, 42, in the direction of the arrow will move the shutter away from the slot, 3, and leave it completely opened permitting articles having the key features to pass into the 55 receiver by gravity. That portion of the cam slot, 40, which produces this movement is only sufficiently long to insure the removal of the shutter from the path of the article or package, and the remaining portion of the cam slot, 40, is of such shape that

the pin, 41, will travel in it without moving the lever, 36.

Movement is also taken from this lever, 36, which in turn derives its movement from the hand lever, 44, for operating the serial 70 numbering wheel or train of wheels. After the package passes the shutter, it is conducted by a gravity-slide or chute 46. By gravity slide is meant a part having a supporting surface upon which the article is adapted to rest disposed at such an angle with relation to the horizon that the article will slide down it by gravity, to proper position to have any desired matter printed upon it by a printing apparatus, which may be said 80 to have a fixed jaw, 47, which carries the printing form and a movable jaw, 48, which corresponds to the platen of a printing press. The fixed jaw is in the form of a box, which is provided with perforated lugs, 85 or ears, 49, secured by bolts or screws to the front wall, 2, of the receiver. The top, 50, of this box is preferably removable, so as to afford access to the contained parts, and one side of the box is in the form of a removable 90 plate, (or plates) 51, which is, in fact, a die plate, and has on its outer face the types of some of the characters which it is desired to print upon the article deposited through the slot, 3. The types for printing the serial 95 numbers on the articles deposited are on the periphery of a wheel, or wheels, 52, 53, etc., and where more than one wheel is used, they are arranged in a train of the kind and having the mode of operation well known to 100 those familiar with adding machines, registers and similar machines. The shaft, 55, of the adding train, is journaled in suitable bearings, formed with or attached to the box, 47, and one end of the shaft projects 105 from the corresponding end of the box and carries a ratchet wheel, 56, the teeth of which are engaged by a pawl, 57, carried by an upwardly extending arm of a link 57^a, the end of which is jointed to the lower arm of the 110 lever, 36, the arrangement of the parts being such that when the hand lever, 44, is pulled down in the direction of the arrow, the pawl will drag over the teeth of the ratchet wheel, and when the hand lever returns to its normal position, as shown in the drawings, the pawl will engage one of the teeth and rotate the shaft 55 through one of its predetermined units of step by step 115 rotation. In this way a number is printed 120 upon each of the articles as they are successively deposited, and the numbers on the successive articles are increased by 1 by each operation.

The die plate, 51, is provided with an 125 opening, 58, through which the numbering wheels are exposed and project far enough to bring the types formed on their peripheries, to the printing plane. The box, 47, is preferably provided with partitions, 59, 60 130

and 61, or as many partitions as the conditions require or make desirable, and these partitions are preferably cast with the back, 62, and bottom, 63, of the box, an advantage of this construction being that it is strong and durable and affords a firm base for the printing apparatus. The partitions also result in compartments, 64, 65, 66 and 67, for containing separate parts of the apparatus. The shaft, 55, of the adding train is preferably continued through the partition, 59, and is provided with a duplicate train of numbering wheels, 52, 53, etc., which are arranged precisely like the numbering train, 52^a, 53^a, etc., so that the number printed by the apparatus will be in duplicate on each article deposited. In addition to this means for numbering the articles, the printing apparatus also has means for printing upon the articles the month, the day of the month and the hour of the day when the article is deposited and the printing is done. For this purpose a time mechanism is contained in a box, 68, that occupies the compartment, 65, and is firmly held against displacement between ribs, or lugs, 69, projecting from the partitions, 59 and 60. A shaft, 70, of this time mechanism, which may correspond with the hand arbor of a clock or watch, projects through an opening in the die plate, 51, and carries a radial arm, 71, which in turn carries a type, 72, which may be shaped to imprint an arrow point. As the shaft, 70, rotates, the arm, 71, moves in a circular depression or counter-sink, 73, surrounding the opening through which the shaft passes, and around this counter-sink the die plate carries the types, 74, of the dial of a clock. The winding stem, 75, of the time mechanism projects through the top, 50, of the box, 47, and has a knurled head, 76, to which access may be had through an opening in the front wall of the receiver, which is kept closed by a door, 77, provided with a lock, 78.

Instead of this means for indicating the hour, the principal objection to which is that it requires too much printing surface on the article, the hour may be printed by a die wheel, 79, which may carry the consecutive numbers from 1 to 24, or, preferably, the numbers from 1 to 12. In this latter instance the hour wheel will derive its movement from the shaft, 70, through suitably arranged bevel gearing 79^a, so that it will make one revolution during each twelve hours, similarly to an ordinary clock. In this event, if A. M. and P. M. are to be indicated, it may be done by a die wheel, 80, carrying the letters "A. M." and "P. M." alternately and deriving its movement from the hour wheel, 79, in which event each complete revolution of the hour wheel will cause the A. M. and P. M. die wheel to move through one of its units of rotation, there-

by alternately changing the indication of the die wheel 80 from A. M. to P. M., and vice versa. In like manner the days of the month may be printed by a die wheel, 81, which derives its movement from the hour wheel, 79, the arrangement being such that each two complete revolutions of the hour wheel will move the die wheel, 81, through one of its units of revolution. Preferably the days of the month are indicated by such a die wheel, 81, which is automatically controlled by the time mechanism as above described, but they may be indicated as shown in Fig. 4 by a similar die wheel, 81^a which is intended to be set manually. Likewise the die wheel, 82, for indicating the months is intended to be set manually, and to this end the die wheel, 81^a, is non-rotatively secured to its shaft, 81^b, and the die wheel, 82, is secured to a sleeve, 83^a, which surrounds said shaft, so that they are capable of free rotation, independently of each other. The shaft and sleeve carry gear wheels, 84 and 85, respectively, and these gear wheels mesh with gear wheels, 86 and 87, respectively, the two peripheries of which are exposed and accessible through an opening, 88, cut through the top, 50, of the box in position to be conveniently reached through the door-way, 77, of the receiver. These wheels, 86 and 87, carry cylindrical flanges, or barrel like portions, 89 and 90, respectively, and these portions, 89 and 90, are marked with the days of the month and the months, respectively, so that an arrow, or index, 91, on the top of the casing will correctly indicate the printing positions of the die wheels, 81 and 82. As the die wheels are arranged relatively to each other, they will print the day after the month, but they will appear in the reverse order on the flanges, 89 and 90, of the indicator. This, however, is immaterial. In order to prevent the random movement of the dating die wheels, they are provided with two wheels, 92 and 93, respectively, which are engaged by light spring dogs, 94, (Fig. 4) which are intended to drag freely over the teeth when the die wheels are being set.

The wrapper of the package comprises an envelop having a pocket portion, 4, a gummed flap, 4^a, and a stub, or check, 5, which projects from one end of the pocket portion, 4, of the envelop. The envelop may bear on either or both of its faces any desired printed matter, and particularly the matter which is commonly used on deposit slips of banks, and more or less of this matter may be duplicated on the pocket portion, 4, and the check, 5. It is also printed preferably on the flap 4^a with the necessary instructions for the guidance of depositors. As shown in Fig. 11, the front face of the envelop and also of the check, has appropriate spaces, 97 and 98, upon

which the printing apparatus already described is adapted to print the date when the package is deposited and the serial number of the deposit, respectively. The pocket portion also has an appropriately designated space, 99, in which the depositor is to write his name and a space, 100, in which to write the number of his account; ordinarily all of the matter appearing in Fig. 11 of the 5 drawing will be printed on the wrapper at the time it is delivered to the depositor for use, with the exception of the matter in the spaces, 97, 98 and 99. The depositor's account number in the space, 100, will probably be printed by a numbering machine before the wrapper is delivered to the depositor. The reverse side of the package is printed with the necessary instructions for depositing it in the receiver. The pocket 10 portion of the wrapper contains a sheet, 6, preferably of stout card-board, and this cardboard is provided with coin pockets, 8, which may be of any desired construction. One face of the card-board has set 15 cured to it a pocket, 103, for paper money, securities, and the like, which it is desired to deposit. This pocket is made of a single sheet of strong paper folded once upon itself, so that one of its leaves forms the bottom of the coin pockets, 8, while the other leaf forms the pocket. The card, 6, is of somewhat greater width than the pocket, 103, and its projecting portion, as already described, forms a key 9 for unlocking the 20 apparatus when the package is presented in the manner described. The key may, if desired, be entirely separate and apart from the wrapper and be a key of any desired construction, adapted for use in customary 25 manner, it being intended that in this event each bank using the apparatus shall provide each of its depositors with a key appropriate thereto, the locks of the apparatus of different banks being made of different 30 combinations of the permutation features 35 in the manner already described.

When the deposited article leaves the chute, 46, it fall into the space between the printing die, 51, and the platen, 48, of the 40 printing apparatus and is there supported in proper position to be printed upon by a stop or platform, 104, consisting of a plate secured to the lower edge of the platen in such manner that it is capable of sliding 45 back and forth as, for instance, by bolts passing through slots in the plate and tapped into the platen, so that their heads bear upon the under side of the plate and support it. This platform is normally held in 50 a projected position so that it crosses the path of the article by light springs, 105, secured at one end to the platen and at the other end to a portion of the platform, 104, which extends rearwardly and is secured 55 to a slide, 106, carrying a pivotal spring 60

pressed pawl, 107, which normally rests upon the circular portion of the periphery of a disk, 108, non-rotatively secured to the main shaft, 43. This disk, 108, carries an eccentrically located pin, 109, which is 65 adapted to engage the top side of an L-shaped push piece, 110, the lower end of which is pivoted to the arm, 111, of a stout lever, which is fulcrumed at 112, and the other arm, 113, of which carries the platen, 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

rock shaft, 131, which passes through the box, 47, from end to end, and is of such shape that when at one extremity of its permitted oscillatory movement with the shaft, 131, as its fulcrum, one of the wheels, 128 or 129, as the case may be, is in mesh with the gear wheel, 127. Any desired means may be employed for holding the wheel, 129, in mesh, or the friction of the parts may be relied upon for this purpose. The end of the shaft 131 opposite that to which the bell-crank lever 130 is secured, carries a similar rigidly attached bell-crank lever 130^a in the arms of which are journaled the ribbon spools 125 and 126, respectively.

It will be observed that the force with which the platen is moved against the printing form is always the same, and is in no sense under the control of the operator. The spring, 116, for doing this work, is made of sufficient strength and in order to prevent unnecessary shocks and jarring of the parts caused by the suddenness of the action of this spring, a block, 132, of rubber or some other cushioning device is used. As shown, this cushioning device is a mere block of rubber, confined in a suitable recess, 133, in the support of the fulcrum bearing of the shaft, 112. After the printing is done and the check is severed, the two parts fall into a gravity chute, 134, through which they pass by gravity and by which they are conducted to their desired destinations. As shown in the drawing, this chute, considered as a whole, is a comparatively wide but narrow tube, which is divided by a partition plate, 135, into two entirely separate distinct branches or chutes, 136 and 137. The severed check falls into the chute, 136, and is conducted thereby to the delivery slot, 138, at the front of the casing, where it is accessible to the depositor. The other chute, 137, may terminate within the receiver, 1, as indicated in Fig. 16, so that all of the deposited packages with their contents are received and contained within the receiver, to be removed by a representative of the bank, access to the receiver being had through an opening which is kept normally closed by a door, 139, at the end of the receiver, as indicated by dotted lines in Fig. 2, or, if desired, the branch, 137, of the chute may be continued through the bottom of the receiver and carried to any desired point, more or less remote from the receiver. For instance, the receiver may be located on the upper floor of a building having a number of stories, and the chute may be carried down through the building to a banking room on a lower floor.

60 room on a lower floor.
It will thus be seen that the receiver is closed excepting for the admission and delivery slots, 3 and 138, respectively, so that the mechanism within the receiver is inac-
65 cessible excepting to authorized persons, at

least to the extent of being protected as against meddlers.

When the hand lever, 44, is released, all of the parts are returned to normal positions by a spring, 140, the receiver being provided with properly disposed stop lugs, 141 and 142, for limiting the movement of the hand lever and other parts in opposite directions. 70

It is not necessary to here describe in detail the great variety of systems in which this apparatus may be used. This is a matter which is left entirely to the discretion and judgment of the bank employing the apparatus in its system of doing business. 80

What we claim as new is:

1. In an apparatus of the class described, the combination of a receiver having an admission slot, printing mechanism located within the receiver in position to receive and print upon articles, comprising separable individual parts deposited through the slot, said printing mechanism having a printing form having separate portions arranged in positions to, at each operation of the apparatus, print upon both of said individual parts, matter or characters indicating a definite mutual serial relation of the individual parts of a given article, when separated, means for operating the printing mechanism so that at each operation of the apparatus it will print upon both of said individual parts, means for severing each deposited article upon a line separating its individual parts from each other, and means for automatically delivering one of said separated parts to the depositor, as a receipt for the other, said receiver being closed to the extent that after the deposited article, while intact, reaches a position to be printed upon it is thereafter inaccessible to the depositor. 85 90 95 100 105

2. In an apparatus of the class described, the combination of a receiver having an admission slot, printing mechanism located 110 within the receiver in position to receive and print upon articles, comprising separable individual parts, deposited through the slot, said printing mechanism having a printing form having separate portions arranged in positions to, at each operation of the apparatus, print upon said individual parts of the article, respectively, matter or characters indicating a definite mutual serial relation of the individual parts of a 120 given article to each other, means for operating said printing mechanism so that at each operation of the apparatus it will print upon both of said individual parts, means for severing each of the deposited articles 125 upon a line separating its individual parts from each other, means for automatically delivering one of said separated parts to the depositor and means for retaining and rendering inaccessible the other of said sep- 130

arated parts, said receiver being closed to the extent that after a deposited article, while intact, reaches a position to be printed upon it is thereafter inaccessible to the depositor, excepting as aforesaid.

3. In an apparatus of the class described, the combination of a receiver having an admission slot, printing mechanism located within the receiver in position to receive and print upon both of two separable individual parts of articles deposited through the slot, a stop for arresting the articles in position to be printed upon, the receiver being closed to the extent of rendering the articles while intact inaccessible after reaching the stop, said printing mechanism having a printing form having separate portions arranged in positions to, at each operation of the apparatus, print upon both of said individual parts, matter or characters indicating a definite mutual serial relation of said parts to each other, means for operating said printing mechanism, means for severing each of the deposited articles upon a line separating its individual parts from each other, means for delivering one of the separated parts to the depositor, and means for retaining and rendering inaccessible the other of said parts, said receiver being closed excepting as aforesaid.

4. In an apparatus of the class described, the combination of a receiver having an admission slot, printing mechanism located within the receiver in position to receive and print upon articles, comprising separable individual parts, deposited through the slot, said printing mechanism having separate portions arranged in positions to, at each operation of the apparatus, print upon both of said individual parts, said printing form having changeable types indicating serial numbers, automatic means operated by each operation of the apparatus for changing said changeable types automatically, means for severing each deposited article upon a line separating its individual parts from each other, and means for delivering one of said separated parts to the depositor, as a receipt for the other, said receiver being closed to the extent that after a deposited article, while intact, reaches the position to be printed upon, it is thereafter inaccessible to the depositor.

5. In an apparatus of the class described, the combination of a receiver having an admission slot, printing mechanism located within the receiver in position to receive and print upon articles, comprising separable individual parts, deposited through the slot, matter or characters indicating a definite mutual serial relation of the individual parts of a given article, when separated, automatic means operated by each operation of the apparatus for severing each deposited article upon a line separating its individual

parts from each other and a gravity slide-way arranged to receive one of the separated parts and automatically deliver it to the depositor, as a receipt for the other of said parts, said receiver being closed to the extent that after a deposited article, while intact, reaches the position to be printed upon, it is thereafter inaccessible to the depositor.

6. In an apparatus of the class described, the combination of a receiver having an admission slot, printing mechanism located within the receiver in position to receive and print upon articles, comprising separable individual parts, said printing mechanism having a printing form having separate duplicate portions arranged in positions to simultaneously print upon both of said individual parts matter or characters indicating a definite mutual serial relation of the individual parts of a given article to each other, means for severing each deposited article upon a line separating its individual parts from each other, automatic means for operating said severing means at each operation of the apparatus and means for delivering one of said separated parts to the depositor, as a receipt for the other, said receiver being closed to the extent that after a deposited article, while intact, reaches a position to be printed upon, it is thereafter inaccessible to the depositor.

7. In an apparatus of the class described, the combination of a receiver having an admission slot, printing mechanism located within the receiver in position to receive and print upon articles comprising separable individual parts deposited through the slot, said printing mechanism having a printing form having separate portions, each of said separate portions having characters appropriate for printing the hours of the day, arranged in positions to print upon both of said individual parts, at each operation of the apparatus, means for severing each of the deposited articles upon a line separating its individual parts from each other, and means for delivering one of said separated parts to the depositor, as a receipt for the other, said receiver being closed to the extent that after a deposited article, while intact, reaches a position to be printed upon, it is thereafter inaccessible to a depositor, excepting as aforesaid.

8. In an apparatus of the class described, the combination of a receiver having an admission slot, printing mechanism located within the receiver in position to receive and print upon articles, comprising separable individual parts, deposited through the slot, said printing mechanism having a printing form having separate portions with duplicate characters appropriate for printing the date, means for operating the printing mechanism whereby the date is printed upon

both of said individual parts, at each operation of the apparatus, means for severing each of the deposited articles upon a line separating its individual parts from each other, and means for delivering one of said separated parts to the depositor, as a receipt for the other, said receiver being closed to the extent that after a deposited article, while intact, reaches a position to be printed upon, it is thereafter inaccessible to the depositor, excepting as aforesaid.

9. In an apparatus of the class described, the combination of a receiver having an admission slot, printing mechanism located within the receiver in position to receive and print upon articles, comprising separable individual parts, deposited through the slot, said printing mechanism having a printing form having separate duplicate portions having changeable characters appropriate for printing serial numbers, said duplicate portions being arranged in positions to print the same serial number upon each of said individual parts, at each operation of the apparatus, means for operating the printing mechanism, automatic means operated at each operation of the apparatus for changing the serial number types of the printing form, means for severing each deposited article upon a line separating its individual parts from each other, and means for delivering one of said separated parts to the depositor, as a receipt for the other, said receiver being closed to the extent that after a deposited article, while intact, reaches a position to be printed upon, it is thereafter inaccessible to the depositor, excepting for the delivery of one of its separate parts, as aforesaid.

10. In an apparatus of the class described, the combination of a receiver having an admission slot, printing mechanism located within the receiver in position to receive and print upon articles, comprising separable individual parts deposited through the slot, said printing mechanism having a printing form having duplicate numbering wheels appropriate for printing serial numbers arranged in positions to print the same serial number on both of said individual parts, at each operation of the apparatus, automatic means operated at each operation of the apparatus for changing the numbering wheels, means for severing each deposited article upon a line separating its individual parts from each other, and means for delivering one of said separated parts to the depositor, as a receipt for the other, said receiver being closed to the extent that after a deposited article, while intact, reaches a position to be printed upon, it is thereafter inaccessible to the depositor, excepting for the delivery of one of its separate parts, as aforesaid.

11. In an apparatus of the class described, the combination of a receiver having an ad-

mission slot, printing mechanism located within the receiver in position to receive and print upon articles, comprising separable individual parts, deposited through the slot, said printing mechanism having a printing form having separate portions arranged in positions to simultaneously print upon both of said individual parts matter or characters indicating a definite mutual serial relation of the individual parts of a given article to each other, means for severing each of the deposited articles upon a line separating its individual parts from each other and means for delivering one of said separated parts to the depositor, as a receipt for the other, said receiver being closed to the extent that after a deposited article, while intact, reaches a position to be printed upon, it is thereafter inaccessible to the depositor, excepting for the delivery of one of its separate parts, as aforesaid.

12. In an apparatus of the class described, the combination of a receiver having an admission slot, a shutter for closing it, printing mechanism located within the receiver in position to receive and print upon articles deposited through the slot, means for automatically conducting the articles deposited through the slot to position to be printed upon, and a lock for locking the shutter in closed position, said receiver being closed to the extent that after a deposited article, while intact, reaches a position to be printed upon, it is thereafter inaccessible to the depositor.

13. In an apparatus of the class described, the combination of a receiver having an admission slot, a shutter for closing it, printing mechanism located within the receiver and in position to receive and print upon the articles deposited through the slot, a lock for locking the shutter closed, and means common to the shutter and printing mechanism for opening the shutter when unlocked, said receiver being closed to the extent that after a deposited article, while intact, reaches a position to be printed upon, it is thereafter inaccessible to the depositor.

14. In an apparatus of the class described, the combination of a receiver having a slot for the admission of articles having permutation features common to a given standard, a shutter for closing said slot, and a permutation lock for locking the shutter closed, said lock having permutation tumblers having portions that are accessible through the slot complementary to the aforesaid permutation features of the article.

15. In an apparatus of the class described, the combination of a receiver having a slot for the admission of articles having permutation features common to a given standard, printing mechanism located within the receiver in position to receive and print upon articles deposited through said slot, a shut-

- ter for closing said slot, a permutation lock for locking the shutter closed, said lock having permutation tumblers having portions accessible through the slot complementary to the permutation features of the article, said receiver being closed to the extent that after a deposited article, while intact, reaches a position to be printed upon, it is thereafter inaccessible to the depositor.
16. In an apparatus of the class described, the combination of a receiver having a slot for the admission of articles having permutation features common to a given standard, a shutter for closing said slot, a permutation lock for locking the shutter closed, said lock having permutation tumblers carried by the shutter, said tumblers having portions accessible through the slot that are complementary to the aforesaid features of the articles, and means for opening the shutter when unlocked.
17. In an apparatus of the class described, the combination with a receptacle having a slot for the admission of articles having permutation features common to a given standard, a shutter adapted to close said slot, a shaft capable of both rotary and longitudinal movement relatively to the shutter and upon which the shutter is mounted, means for normally preventing the shaft from rotating, said shaft being provided with both circumferential and longitudinal grooves, resulting in corresponding shoulders, a plurality of permutation tumblers pivoted to and carried by the shutter, said tumblers having fingers which project in different angular directions from the pivotal axes of the tumblers, and which normally project into the circumferential grooves of the shaft, means for moving the shaft endwise and thereby freeing it from the means for normally preventing its rotation and also bringing the fingers of the tumblers into the longitudinal grooves, and means for thereafter rotating the shaft to move the shutter.
18. In an apparatus of the class described, the combination of a practically closed receiver having an admission slot, printing mechanism located within the receiver and in position to receive and print upon articles deposited through the slot, and a lock for locking the printing mechanism and preventing its operation and for also locking the shutter closed, said lock having permutation tumblers accessible through the slot, and common mechanism for opening the shutter when unlocked and thereafter operating the printing mechanism.
19. In an apparatus of the class described, the combination of a practically closed receiver having an admission slot, a shutter therefor having means for preventing the admission of inappropriate articles, printing mechanism located within the receiver

and in position to receive and print upon articles deposited through the slot, and a lock for locking both the shutter and the printing mechanism.

20. In an apparatus of the class described, the combination of a receiver having an admission slot, a shutter therefor, printing mechanism located within the receiver and in position to receive and print upon articles deposited through the slot, a gravity chute leading from the admission slot to the printing mechanism for conducting the deposited articles from the slot to proper position to be received and printed upon by the printing mechanism, a lock for locking the shutter closed, said lock having permutation tumblers and means operating through the medium of the lock for opening the shutter when unlocked.

21. In an apparatus of the class described, the combination of a receiver having an admission slot, a shutter therefor, printing mechanism located within the receiver, a gravity chute leading from the admission slot to the printing mechanism for conducting the articles to proper position to be received and printed upon by the printing mechanism, a lock for locking the shutter closed, and connections between the shutter and printing mechanism for preventing the operation of the printing mechanism while the shutter is closed.

22. In an apparatus of the class described, the combination of a receiver having an admission slot, printing mechanism located within the receiver, a gravity chute extending from the admission slot to the printing mechanism for conducting the articles into position to be printed upon, said printing mechanism having means for printing upon the articles, matter or characters indicating the time when the articles are deposited, respectively, and time mechanism for operating the time indicating parts of the printing mechanism, said receiver being closed to the extent that after a deposited article reaches a position to be printed upon, it is thereafter inaccessible to the depositor.

23. In an apparatus of the class described, the combination of a receiver having an admission slot, printing mechanism located within the receiver, a gravity chute extending from the slot to the printing mechanism for conducting the articles into position to be printed upon, said printing mechanism having changeable types for printing upon the articles matter or characters indicating the hour of the day and the day of the month when the articles are deposited, respectively, and time mechanism for automatically changing the types of the printing mechanism, said receiver being closed to the extent that after a deposited article reaches a position to be printed upon, it is thereafter inaccessible to the depositor.

24. In an apparatus of the class described, the combination of a receiver having an admission slot, printing mechanism located within the receiver, a gravity chute extending from the slot to the printing mechanism for conducting the articles into position to be printed upon, said printing mechanism having a manually operable type wheel for indicating the month and having also type wheels for indicating the day of the month and the hour of the day, respectively, and time mechanism for operating the month, day and hour type wheels of the printing mechanism, said receiver being closed to the extent that after a deposited article reaches a position to be printed upon, it is thereafter inaccessible to the depositor.
25. In an apparatus of the class described, the combination of a receiver having an admission slot and a delivery slot, printing mechanism located within the receiver and thereby rendered inaccessible, said printing mechanism being also located in position to receive and print upon articles deposited through the slot and comprising separable individual parts, said printing mechanism having means for printing upon the individual parts of the article duplicate serial identification marks, means for severing the deposited article upon a line separating its individual parts and between the duplicate identification marks, and a gravity chute for conducting one of the severed parts to the delivery slot, said receiver being closed to the extent that after a deposited article reaches a position to be printed upon, it is thereafter inaccessible to the depositor.
26. In an apparatus of the class described, the combination of a receiver having an admission slot and a delivery slot, printing mechanism located within the receiver and in position to receive and print upon articles comprising separable individual parts that are deposited through the admission slot, means for severing the deposited article upon a line separating its individual parts and between the imprints thereon and a plurality of gravity chutes for conducting the severed parts to different destinations, respectively, said receiver being closed to the extent that after a deposited article reaches a position to be printed upon, it is thereafter inaccessible to the depositor.
27. In an apparatus of the class described, the combination of a receiver having an admission slot, a shutter therefor, a lock for locking said shutter closed, printing mechanism located in position to receive and print upon articles deposited through the slot, manually operable means for opening the shutter when unlocked and means operated by said manually operable means for operating the printing mechanism.
28. In an apparatus of the class described, the combination of a receiver having an admission slot, an article having separable individual parts, one of said parts consisting of a pocket having printed thereon matter appropriate to its purposes, and the other of said individual parts consisting of a check or receipt having matter thereon appropriate to its purposes, and each of said individual parts having appropriate spaces for receiving printed matter, printing mechanism located in position to receive and print upon the article deposited through the admission slot, said printing mechanism having separate printing forms adapted to print in the aforesaid blanks of the article, said printing forms having types adapted to print mutual serial identification characters or marks on both the pocket part and the check or receipt part of the article deposited, means for severing the check or receipt part from the pocket part, and means for delivering them at different destinations.
29. In an apparatus of the class described, the combination of a receiver having an admission slot and a delivery slot, an article having separable individual parts, one of said parts consisting of a pocket and the other consisting of a check or receipt, printing mechanism having separate printing forms located in positions to print upon the individual parts of the article, respectively, said printing forms having types adapted to print duplicate identification characters or marks, said printing forms also being so located that at each operation of the apparatus they imprint both of said individual parts, means for severing the check or receipt part from the pocket part and means for conducting the check or receipt and pocket to different points or destinations.
30. In an apparatus of the class described, the combination of a receiver having a slot for the admission of articles having permutation features common to a given standard, a shutter for said slot having tumblers having permutation features corresponding with the permutation features of the article deposited, whereby the introduction through the slot of an article having appropriate permutation features moves the tumblers and frees the shutter, permitting it to be opened manually.
